HANDLE FOR FENCING ÉPÉE OR FOIL

John H. Culling, 620 N. Taylor Ave., Kirkwood, Mo.
63122, and Emil Stanley St. Pellicer, 6317 Clayton
Road, St. Louis, Mo. 63117

Filed Oct. 26, 1973, Ser. No. 410,266

Term of patent 14 years

Int. Cl. D22—02

U.S. Cl. D22—1

FIG. 1

FIG. 2

FIG. 3

FIG. 4

FIG. 5

FIG. 6

FIG. 7

FIG. 1 is a view in perspective of a handle for fencing épée or foil embodying our new design;

FIG. 2 is a left side elevation of our handle for fencing épée or foil;

FIG. 3 is a right side elevation of our handle for fencing épée or foil;

FIG. 4 is a front elevation;

FIG. 5 is a rear elevation;

FIG. 6 is a top plan view; and

FIG. 7 is a bottom plan view.

We claim:

The ornamental design for a handle for fencing épée or foil, substantially as shown.
